CAP

Mary Briers, Houston, Tex.

Application March 4, 1953, Serial No. 23,890

Term of patent 14 years

(Cl. D3—13)

To all whom it may concern:

Be it known that I, Mary Briers, a citizen of the United States and a resident of Houston, in the county of Harris and State of Texas, have invented a new, original, and ornamental Design for a Cap, of which the following is a specification, reference being had to the accompanying drawing, forming a part hereof.

Referring to the drawing:

Fig. 1 is a side elevational view of a cap showing my new design;

Fig. 2 is a top plan view; and

Fig. 3 is a front elevational view thereof.

I claim:

The ornamental design for a cap, as shown.
MARY BRIERS.
